Application April 14, 1932, Serial No. 605,204

9 Claims. (Cl. 221—95)

This invention relates to automatic locking means for dispensers and in particular relates to means whereby the dispensing nozzle may not be replaced on its hook until the operator has performed a certain function, such as causing the main operating shaft of a registering machine to be operated. In our application for Recording dispenser, Serial Number 578,758, filed December 3, 1931, we showed a recording dispenser which 5 was adapted to pump any predetermined quantity of a fluid such as gasoline, to record the number of gallons dispensed and the total price to be paid therefor and after the gasoline was issued the operator would press a button which 10 would operate the main operating shaft of a printing or registering mechanism which would print and issue a ticket and would print a record to be retained within the machine. The object of the present invention is to add a locking mechanism to the mechanism shown in the said application whereby the operator cannot hang the nozzle on its hook until he has pressed the button which causes a motor to operate the main operating shaft and thereby to print and issue the 15 ticket.

In the drawings:

Fig. 1 is an elevational view, partly fragmentary, of the pump having the present invention incorporated therein;

Fig. 2 is an elevational view of the frame of the registering mechanism having a part of our invention incorporated therein; and

Fig. 3 is a detail view of the nozzle.

As shown in the said application, a casing 1 is provided in which is enclosed a motor 2 which drives a shaft 3 on which is mounted a worm 4 which meshes with and drives a gear 5 which is operatively connected to a main operating shaft 6. It is this main operating shaft which operates the printing mechanism shown in the said application and which forms no part of the present invention and hence is not described. It may be mentioned, however, that this main operating shaft is not operated until the operator presses in on a button 7. The hose 8 encloses a Bowden wire 9 which extends to the nozzle 10 and ends in a button 11 which is engaged by a lever handle 12 pivoted on a pin 13 so that when the handle 12 is pressed by the operator the Bowden wire is pulled towards the end of the nozzle. The other end of the Bowden wire is connected by a pin 14 to a lever 15 pivoted on a pin 16. The lower end of the lever 15 is provided with a pin 17 which is connected to a rod 18 suspended by a link 19 pivotally mounted on a shaft 20. A pin 21 connects

the rod 18 to a link 22 which is connected to a pin 23 which is mounted on a bell crank lever 24 pivoted on a pin 25. The lower arm of the bell crank lever 24 is connected by a pin 26 to a rod 27 which is connected by means of a pin 28 to a lever 29 pivoted on a pin 30. The lever 29 is provided with a pin 31 on which is hung a link 32 provided with a slot 33 and a pin 34. A pin 35 is mounted on the frame 36 of the registering mechanism and extends through the slot 33 serving as a guide therefor. The pin 34 underlies a lever 37 pivoted on a pin 38 carried by the frame 36 and is provided with a latching finger 39. The lever 37 is also provided with a pin 40 on which is hung a rod 41 which is bifurcated at its lower end and straddles the shaft 6. It is also provided with a pin 42 on which is mounted a roller 43 which is normally seated in a depression 44 of a cam disk 45 secured to the shaft 6.

The nozzle 10 is normally hung on a hook 46 pivoted on a pin 47, which hook 46 has a rearwardly extending arm 48 to which is attached a rod 49 by means of a pin 50. The lower end of the rod 49 is attached to a pin 51 which is mounted on a slide 52. The rod 49 is normally pulled downwardly by means of a spring 53. The slide 52 is provided with two slots 54 and 55 which receive pins 56 and 57 respectively mounted on the side wall 36 of the registering machine. The slide 52 is also provided with a laterally extending arm 58 which carries a pin 59 on which is mounted a roller 60. The roller 60 normally lies adjacent an abrupt wall 61 of a disk 62 which is provided with a cam channel 63.

In operation the attendant, when he wishes to dispense the fluid such as gasoline, removes the nozzle 10 from the hook 46. When the attendant depresses the handle 12, he pulls the Bowden wire 9 so as to partially rotate the lever 15 anticlockwise thereby pushing the rod 18 and link 22 to the right as viewed in Fig. 1 and rotating the bell crank lever 24 clockwise elevating the rod 27 and partially rotating the lever 29 clockwise as viewed in Figs. 1 and 2, thereby elevating the link 32 and partially rotating the lever 37 clockwise removing the latching finger 39 out of the notch 64 in the lower portion of the slide 52. The slide 52 and rod 49 are now free so that they may drop by gravity assisted by the spring 53. When the slide 52 moves downwardly the roller 60 is moved beneath the abrupt wall 61 of the disk 62 and the notch 65 in the slide 52 above the notch 64 is now adjacent the latching finger 39. The parts remain in this position as long as the operator is dispensing the

fluid such as gasoline, by pressing the handle 12. The moment he releases the handle 12 a spring 66 presses downwardly on an arm 67 secured to the lever 15 and pulls the Bowden wire 9 back to its normal position, which depresses the rod 21 and link 32 so as to move the pin 34 away from the lever 37 whereupon the lever 37 falls by gravity so that the latching finger 39 is projected into the notch 65 which holds the rod 49 in its lowermost position so that the outer end of the hook 46 engages a plate 88 of the frame so that the nozzle cannot be hung on the hook.

As shown in the above mentioned application, when the operator presses the button 1 the main operating shaft 6 is rotated one revolution. As soon as the said shaft 6 commences its revolution in a clockwise direction, as viewed in Fig. 2, the cam surface 69 of the cam disk 45 engages the roller 43 and elevates the rod 41 partially rotating the lever 37 in a clockwise direction, as viewed in Fig. 2, and removing the latching finger 39 out of the notch 65. The roller 60 carried by the slide 52 is now in the cam channel 63 so that the cam 10, forming the inner surface of the cam channel 63, engages and elevates the roller 60, slide 52 and rod 43, thereby lowering the hook 46 to the position shown in Fig. 1 so that the nozzle can be again hung thereon. As the shaft 6 completes its revolution the roller 43 sinks into the depression 44 of the cam disk 45 so that the latching finger 39 is moved by gravity into the notch 64.

It is, therefore, apparent that when the operator presses on the nozzle handle the hook is moved into a position such that the nozzle cannot be again hung thereon until after the operator has completed the dispensing of the fluid and has also performed a subsequent operation, such as pressing on the button 1, which as shown in the said copending application causes the shaft 6 to be operated to print a ticket and this operation automatically moves the hook 46 into such a position that the hose can again be hung thereon.

We realize that many changes may be made in the specific form of this invention shown and described by way of illustration in this application and we, therefore, reserve the right to make such changes in the specific form of the invention as shown herein as we may find to be desirable. We, therefore, claim the invention broadly except as we may limit ourselves by the appended claims.

Having now described our invention, we claim:

1. In a dispenser, a discharge nozzle, a lever mounted thereon, a hook on which said nozzle is hung when not in use, and means whereby when said lever is operated said hook will be moved into a position where it cannot be used to support said nozzle.

2. In a dispenser, a discharge nozzle, a lever mounted thereon adapted to dispense a fluid when the lever is operated, a support for said nozzle on which said nozzle is adapted to be hung when the dispenser is not in use, and means to move said support to a position where it cannot be used to support said nozzle when the said lever is operated.

3. In a dispenser, a discharge apparatus, a hook to normally support said discharge apparatus, means to displace said hook so that said discharge apparatus cannot be hung on said hook when said discharge apparatus has been actu-

ated, a member adapted to be actuated by the operator after the discharge apparatus has performed its function, and means controlled by said member to move said hook to its normal position when the said member has been operated. 5

4. In a dispenser, a discharge nozzle, a hook on which said discharge nozzle is normally suspended, a plate, a lever carried by said nozzle and adapted to control the dispensing of a fluid when operated, and means operatively connecting said lever and hook so that when said lever is operated the hook is moved towards said plate so that the nozzle cannot be hung on said hook. 10

5. In a dispenser, a discharge nozzle, a hook on which said discharge nozzle is normally suspended, a lever carried by said nozzle and adapted to control the dispensing of a fluid when operated, a second lever, means operatively connecting said levers, and means operatively connecting said second lever and hook so that when said nozzle is displaced from said hook and the first mentioned lever has been operated, said hook will be locked in a position where the nozzle cannot be suspended thereon. 15

6. In a dispenser, a lever, means controlled by the lever to dispense a fluid, a hook on which said lever is normally hung, a link connected to said hook, a latch normally holding the link against movement, means controlled by the lever whereby said latch is displaced so as to permit said link to be actuated when said lever is operated, and means to displace said link when the latch has been operated. 25

7. In a dispenser, a lever, means controlled by the lever to dispense a fluid, a hook on which said lever is normally hung, a plate, a slide provided with a notch, means connecting said slide with said hook, a latch, said latch being normally engaged in said notch and holding said hook in a position such that the lever may be hung thereon, means operatively connecting said latch and lever so that when said lever is operated said latch will be displaced from the said notch, and means whereby when the latch is moved towards said plate the hook will be displaced so that the lever 45 cannot be suspended thereon. 40

8. In a dispenser, a discharge nozzle, a hook on which said discharge nozzle is normally suspended, a slide provided with two notches, means connecting said slide and hook, a lever connected to said nozzle and adapted to control the flow of liquid therefrom, a latch adapted to engage either of the notches in said slide, means controlled by said lever when operated to remove said latch from out of said notches, and means to thereupon move said hook to a position in which the nozzle cannot be hung thereon. 55

9. In a dispenser, a discharge nozzle, a hook on which said discharge nozzle is normally suspended, a slide provided with two notches, means connecting said slide and hook, a lever connected to said nozzle and adapted to control the flow of liquid therefrom, a latch adapted to engage either of the notches in said slide, means controlled by said lever when operated to remove 60 said latch from out of said notches, means to thereupon move said hook to a position in which the nozzle cannot be hung thereon, and means whereby the release of said lever causes said hook to be locked against being moved into a position 65 where the nozzle can be hung thereon.
